UNITED STATES PATENT OFFICE.

WILLIAM J. LOOFS AND CHARLES C. COX, OF HOUSTON, TEXAS.

SAMPLE-TAKING DEVICE.

Application filed January 10, 1921, Serial No. 436,347. Renewed November 18, 1922.

To all whom it may concern:

Be it known that we, WILLIAM J. LOOFS and CHARLES C. COX, citizens of the United States, residing at Houston, in the county of Harris and State of Texas, have invented certain new and useful Improvements in a Sample-Taking Device, of which the following is a specification.

This invention relates to new and useful improvements in a sample taking device.

One object of the invention is to provide a device of this character whereby samples of the strata being pierced, in drilling oil wells, may be obtained.

With the above and other objects in view the invention has particular relation to certain novel features of construction, arrangement of parts and use, an example of which is described in this specification and illustrated in the accompanying drawings, wherein:—

The figure is a vertical sectional view of the device.

Referring now more particularly to the drawing, the numeral 1 designates a tubular drill stem to the lower end of which the core barrel 2 is secured by the collar 3. The lower end of said barrel is reinforced by a drilling shoe 8 which is toothed so as to pierce the strata as the stem is rotated and the stem 1 has the ports, as 4, through which flushing water forced down through the stem reaches the cutting end of the shoe. The

upper end of the barrel 2 is closed by the plate 5 which is threaded into the collar 3 between the lower end of the stem and the upper end of the barrel. A rod 6 is attached at its upper end to the plate 5, said rod forming the shank of the auger 7, which is carried by the lower end of said rod.

As the stem 1 is rotated, in the usual way, the shoe 8 pierces the strata and the auger 7 forces the cuttings up into the core barrel. As the barrel is filled the water and slush therein pass out through the ports 9 thereof. When the barrel has received sufficient sample it may be withdrawn for inspection and during the process of withdrawal the auger will retain the cuttings in the barrel.

What we claim is:

A sample taking device including a tubular stem having an outlet port, a core barrel attached to the lower end thereof and provided with a port, a plate closing the upper end thereof, a drill shoe attached to the lower end thereof, and an auger anchored to said plate and depending within said barrel.

In testimony whereof we have signed our names to this specification in the presence of two subscribing witnesses.

WILLIAM J. LOOFS.
CHARLES C. COX.
